UNITED STATES PATENT OFFICE.

ARTHUR C. HOPKINS, OF NILES, MICHIGAN, ASSIGNOR TO NATIONAL STANDARD COMPANY, OF NILES, MICHIGAN.

LIFTING JACK.

Application filed April 9, 1927. Serial No. 182,313.

My present improvements relate to improvements in lifting jacks of the type shown in Letters Patent No. 1,559,098, dated October 27, 1925.

- 5 The main object of this invention is to provide an improved actuating means whereby the lifting member may be rapidly raised and lowered, at the same time one which has a large amount of power.
- 10 A further object is to provide an improved actuating means which can be quickly reversed or adjusted for raising or lowering the load.

Objects relating to details and economies 15 of construction and operation of the invention will appear from the detailed description to follow.

The invention is defined and pointed out in the claims.

- 20 A structure which is a preferred embodiment of my invention is illustrated in the accompanying drawing, forming a part of this specification, in which:

Fig. 1 is a perspective view of a lifting jack 25 embodying the features of my invention, the actuating lever being shown in its down or lowered position.

Fig. 2 is a perspective view with the actuating lever in raised position, the lifting 30 lever being in partially elevated position.

Fig. 3 is a fragmentary inverted view of the actuating lever and certain parts directly associated therewith.

Fig. 4 is a fragmentary view partially in 35 section on line 4—4 of Fig. 3.

Fig. 5 is a fragmentary view of certain of the parts shown in Fig. 4, swung or adjusted to another position.

In the drawing similar reference characters 40 refer to similar parts throughout the several views.

Referring to the drawings, I provide a frame consisting, in the embodiment illustrated, of side members 1, 1 connected by suitable cross pieces and provided with wheels 2 mounted on the axle 3 and with caster wheels 4 mounted on laterally projecting brackets 5.

The lifting lever 6 is mounted on the pivot 50 7 extending between the side members of the frame. This lifting lever carries the head 8 which is pivoted at the outer end of the lever 6 at 9, the lever being held in upright position by the link 10 which is pivoted to the head at 11 and to the frame at 12 in par-

allel relation to the lever, thereby holding the head in upright position during the swing of the lifting lever.

I connect a pair of racks 13 to the lifting lever by means of pivots 14, the pivot 14 being arranged in spaced relation to the pivot 7. These levers are supported on rollers 15 carried by a cross piece 16 on the frame.

The pinions 17 are supported by the journals 18 to coact with the racks. Between the pinions and connected thereto is a ratchet wheel 19. At each side of the ratchet wheel is a bearing 20 for the forks 21 of the actuating lever, designated generally by the numeral 22. This actuating lever is provided 70 with a cross bar or hand piece 23 at its outer end.

A lifting pawl 24 is mounted on the pivot 25 carried by the lever to coact with the ratchet wheel, the pawl being urged yielding- 75 ly into engagement with the ratchet wheel by means of the spring 26, one end of which engages the arm 27 on the pawl and the other a support 28 provided therefor on the actuating lever.

A holding pawl 29 is pivoted on the frame at 30 to coact with the ratchet wheel, this holding pawl being arranged at the rear of the ratchet wheel and provided with an upwardly projecting pin or finger 31 to which 85 the spring 32 is connected, the spring acting to urge the pawl into engagement with the ratchet.

In normal lifting operation, the lifting pawl ratchets upon the ratchet wheel as the 90 actuating lever is oscillated, the holding pawl also ratcheting upon the teeth of the ratchet wheel to prevent reverse rotation of the ratchet.

To lower or reverse the jack, I provide a 95 reversing member 33 which has a rearwardly projecting finger 34 curved to extend over one of the bearings of the actuating lever in to co-operating relation with the pin 35 on the pawl 29. This reversing member is 100 mounted for a combined reciprocating and swinging movement, the reversing member being slotted at 36 to engage the bolt 37 and also having a slot 38 embracing the pivot 25, the slot 38 being of such dimensions as to allow a swinging as well as a reciprocating movement about the pivot bolt 37.

At its rear end, the reversing member has a cam 39 coacting with pin 40 so that as the reversing member is moved rearwardly, it is 110

also given an upward swinging movement, the combined movement giving a quicker and longer lift to the holding pawl than would result from a mere reciprocatory movement.

The reversing rod 41 is provided with a grip 42 positioned so as to be grasped along with the hand piece 23 of the actuating lever. At its outer end, this reversing rod 41 is provided with a cross piece 43, the cross piece being pivoted to the rod at 44. The link 45 is connected to one end of this cross piece by the pivot 46, the other end of the link being connected to the lower end of the tripping lever 47.

This lever 47 is mounted on the pivot 25 and at its upper end is provided with a pin 48 engaging the slot 49 in the upwardly projecting part 50 of the reversing member. This connection permits of the reciprocating and swinging movement of the reversing member. The lifting pawl 24 is connected by the link 51 which is connected to the cross bar by the pivot 52 to the lifting pawl, the link 51 having a slot 53 therein engaging a pin 54 on the lifting pawl, allowing for a lost motion connection so that on the lifting movement of the jack, the pawl can ratchet or oscillate independently of the reversing means.

A spring 55 is connected to the lower end of the lever 47 and to the lug 56 on the actuating lever, so that the reversing member is returned to its inoperative position.

With the parts thus arranged, the operation of the jack is as follows. Assuming the parts to be in the lowered position shown in Fig. 1, it is only necessary to oscillate the actuating lever 22 to raise the lifting member. When it is desired to lower the lifting member, the operator, with the actuating lever near its horizontal position, presses downwardly thereon and at the same time pulls on the reversing rod with the grip 42. As soon as the holding pawl is relieved of its load, the reversing member moves rearwardly and upwardly, disengaging the holding pawl from the ratchet wheel and allowing the ratchet wheel to turn in a reverse direction under the control of the actuating lever. When the actuating lever reaches the end of its up-stroke, the reversing member is released and returned to its initial position by the spring 55, allowing the holding pawl to drop into engaging position. The load is then shifted from the lifting pawl to the holding pawl, allowing the holding pawl to be retracted by a pull on the reversing rod. The pin on the holding pawl prevents movement of the reversing member, thereby permitting the actuating lever to be swung down for a second stroke.

I have illustrated and described my improvements in an embodiment which I have found very practical. I have not attempted to illustrate or describe certain modifications

and adaptations which I contemplate as it is believed this disclosure will enable those skilled in the art to embody or adapt my improvements as may be desired.

Having thus described my invention, what I claim as new and desire to secure by Letters Patent, is:

1. In a lifting jack, the combination of a frame, a lifting member pivotally mounted on said frame, a pair of rack bars pivotally connected to said lifting member in spaced relation to its pivot, pinions coacting with said rack bars journaled in said frame, a ratchet wheel disposed between and connected to said pinions and having actuating lever bearings at its sides, an actuating lever forked to embrace said ratchet wheel and pivotally mounted on said bearings at the sides thereof, a spring actuated lifting pawl pivotally mounted on said actuating lever to coact with said ratchet wheel, a spring actuated holding pawl pivotally mounted on said frame at the rear of said ratchet wheel to coact therewith, a reversing member mounted on said actuating lever for reciprocating and swinging movement and having a curved finger coacting with said holding pawl, said reversing member being provided with a cam and said lever with a coacting pin whereby a swinging movement is imparted to the reversing member as it is reciprocated, a reversing rod mounted on said actuating lever, a cross bar pivotally connected to said rod, a link connected to one end of said cross bar and having a pin and slot connection with said lifting pawl, a reversing member lever pivotally mounted on said actuating lever and having a pin and slot connection with said reversing member, a link connecting the opposite end of said cross bar with said reversing member lever, and a return spring connected to said reversing member lever.

2. In a lifting jack, the combination of a frame, a lifting member pivotally mounted on said frame, a pair of rack bars pivotally connected to said lifting member in spaced relation to its pivot, pinions coacting with said rack bars journaled in said frame, a ratchet wheel disposed between and connected to said pinions and having actuating lever bearings at its sides, an actuating lever forked to embrace said ratchet wheel and pivotally mounted on said bearings at the sides thereof, a spring actuated lifting pawl pivotally mounted on said actuating lever to coact with said ratchet wheel, a spring actuated holding pawl pivotally mounted on said frame at the rear of said ratchet wheel to coact therewith, a reversing member mounted on said actuating lever for reciprocating and swinging movement and having a curved finger coacting with said holding pawl, said reversing member being provided with a cam and said lever with a coacting pin whereby

a swinging movement is imparted to the reversing member as it is reciprocated, a reversing rod mounted on said actuating lever, a cross bar pivotally connected to said rod, a link connected to one end of said cross bar and having a pin and slot connection with said lifting pawl, operating connections for the other end of said cross bar to said reversing member, and a return spring for said reversing member.

3. In a lifting jack, the combination of a frame, a lifting member pivotally mounted on said frame, a pair of rack bars pivotally connected to said lifting member in spaced relation to its pivot, pinions coacting with said rack bars journaled in said frame, a ratchet wheel disposed between and connected to said pinions and having actuating lever bearings at its sides, an actuating lever forked to embrace said ratchet wheel and pivotally mounted on said bearings at the sides thereof, a spring actuated lifting pawl pivotally mounted on said actuating lever to coact with said ratchet wheel, a spring actuated holding pawl pivotally mounted on said frame to coact with said ratchet wheel, a reversing member mounted on said actuating lever to coact with said holding pawl, a reversing rod mounted on said actuating lever, a cross bar pivotally connected to said rod, a link connected to one end of said cross bar and having a pin and slot connection with said lifting pawl, a reversing member lever pivotally mounted on said actuating lever and having a pin and slot connection with said reversing member, a link connecting the opposite end of said cross bar with said reversing member lever, and a return spring connected to said reversing member lever.

4. In a lifting jack, the combination of a frame, a lifting member pivotally mounted on said frame, a pair of rack bars pivotally connected to said lifting member in spaced relation to its pivot, pinions coacting with said rack bars journaled in said frame, a ratchet wheel disposed between and connected to said pinions and having actuating lever bearings at its sides, an actuating lever forked to embrace said ratchet wheel and pivotally mounted on said bearings at the sides thereof, a spring actuated lifting pawl pivotally mounted on said actuating lever to coact with said ratchet wheel, a spring actuated holding pawl pivotally mounted on said frame to coact with said ratchet wheel, a reversing member mounted on said actuating lever to coact with said holding pawl, a reversing rod mounted on said actuating lever, a cross bar pivotally connected to said rod, a link connected to one end of said cross bar and having a pin and slot connection with said lifting pawl, operating connections for the other end of said cross bar to said reversing member, and a return spring for said reversing member.

5. In a lifting jack, the combination of a frame, a lifting member pivotally mounted on said frame, a rack bar pivotally connected to said lifting member in spaced relation to its pivot, a pinion coacting with said rack bar, a ratchet wheel connected to said pinion, an actuating lever, a spring actuated lifting pawl pivotally mounted on said actuating lever to coact with said ratchet wheel, a spring actuated holding pawl pivotally mounted on said frame at the rear of said ratchet wheel to coact therewith, a reversing member mounted on said actuating lever for reciprocating and swinging movement and having a curved finger coacting with said holding pawl, said reversing member being provided with a cam and said lever with a coacting pin whereby a swinging movement is imparted to the reversing member as it is reciprocated, a reversing rod mounted on said actuating lever and having a pin and slot connection with said reversing member, a link connecting the opposite end of said cross bar with said tripping lever, and a return spring connected to said tripping lever.

6. In a lifting jack, the combination of a frame, a lifting member pivotally mounted on said frame, a rack bar pivotally connected to said lifting member in spaced relation to its pivot, a pinion coacting with said rack bar, a ratchet wheel connected to said pinion, an actuating lever, a spring actuated lifting pawl pivotally mounted on said actuating lever to coact with said ratchet wheel, a spring actuated holding pawl pivotally mounted on said frame at the rear of said ratchet wheel to coact therewith, a reversing member mounted on said actuating lever for reciprocating and swinging movement and having a curved finger coacting with said holding pawl, said reversing member being provided with a cam and said lever with a coacting pin whereby a swinging movement is imparted to the reversing member as it is reciprocated, a reversing rod mounted on said actuating lever, a cross bar pivotally connected to said rod, a link connected to one end of said cross bar and having a pin and slot connection with said lifting pawl, and operating connections for the other end of said cross bar to said reversing member.

7. In a lifting jack, the combination of a frame, a lifting member pivotally mounted on said frame, a rack bar pivotally connected to said lifting member in spaced relation to its pivot, a pinion coacting with said rack bar, a ratchet wheel connected to said pinion, an actuating lever, a spring actuated lifting pawl pivotally mounted on said actuating lever to coact with said ratchet wheel,

- a spring actuated holding pawl pivotally mounted on said frame to coact with said ratchet wheel, a reversing member mounted on said actuating lever to coact with said holding pawl, a reversing rod mounted on said actuating lever, a cross bar pivotally connected to said rod, a link connected to one end of said cross bar and having a pin and slot connection with said lifting pawl, a tripping lever pivotally mounted on said actuating lever and having a pin and slot connection with said reversing member, a link connecting the opposite end of said cross bar with said tripping lever, and a return spring connected to said tripping lever.
8. In a lifting jack, the combination of a frame, a lifting member pivotally mounted on said frame, a rack bar pivotally connected to said lifting member in spaced relation to its pivot, a pinion coaxing with said rack bar, a ratchet wheel connected to said pinion, an actuating lever, a spring actuated lifting pawl pivotally mounted on said actuating lever to coact with said ratchet wheel, a spring actuated holding pawl pivotally mounted on said frame to coact with said ratchet wheel, a reversing member mounted on said actuating lever to coact with said holding pawl, a reversing rod mounted on said actuating lever, a cross bar pivotally connected to said rod, a link connected to one end of said cross bar and having a pin and slot connection with said lifting pawl, and operating connections for the other end of said cross bar to said reversing member.
9. In a lifting jack, the combination of a frame, a lifting member, a rack bar operatively associated with said lifting member, a pinion coaxing with said rack bar, a ratchet wheel connected to said pinion, an actuating lever, a lifting pawl pivotally mounted on said actuating lever to coact with said ratchet wheel, a holding pawl pivotally mounted on said frame to coact with said ratchet wheel, a reversing member mounted on said actuating lever for reciprocating and swinging movement to coact with said holding pawl, a reversing rod slidably mounted on said actuating lever, a spring acting to hold said reversing member normally in inoperative position, and operating connections for said reversing rod and lifting pawl and said reversing rod and reversing member whereby the pawls are alternately disengaged by the actuation of said reversing rod, said lifting pawl having a lost motion connection to said reversing rod.
10. In a lifting jack, the combination of a frame, a lifting member, a rack bar operatively associated with said lifting member, a pinion coaxing with said rack bar, a ratchet wheel connected to said pinion, an actuating lever, a lifting pawl pivotally mounted on said actuating lever to coact with said ratchet wheel, a holding pawl pivotally mounted on said frame to coact with said ratchet wheel, a reversing member mounted on said actuating lever to coact with said holding pawl, a reversing rod slidably mounted on said actuating lever, a spring acting to hold said reversing member normally in inoperative position, and operating connections for said reversing rod and lifting pawl and said reversing rod and reversing member whereby the pawls are alternately disengaged by successive actuations of said reversing rod.
11. In a lifting jack, the combination of a frame, a lifting member, a ratchet wheel operatively connected to said lifting member, an actuating lever, a lifting pawl pivotally mounted on said actuating lever to coact with said ratchet wheel, a holding pawl pivotally mounted on said frame to coact with said ratchet wheel, a reversing member mounted on said actuating lever for reciprocating and swinging movement to coact with said holding pawl, a reversing rod slidably mounted on said actuating lever, a spring acting to hold said reversing member normally in inoperative position, and operating connections for said reversing rod and lifting pawl and said reversing rod and reversing member whereby the pawls are alternately disengaged by successive actuations of said reversing rod, said lifting pawl having a lost motion connection to said reversing rod.
12. In a lifting jack, the combination of a frame, a lifting member, a ratchet wheel operatively connected to said lifting member, an actuating lever, a lifting pawl pivotally mounted on said actuating lever to coact with said ratchet wheel, a holding pawl pivotally mounted on said frame to coact with said ratchet wheel, a reversing member mounted on said actuating lever to coact with said holding pawl, a reversing rod slidably mounted on said actuating lever, a spring acting to hold said reversing member normally in inoperative position, and operating connections for said reversing rod and lifting pawl and said reversing rod and reversing member whereby the pawls are alternately disengaged by successive actuations of said reversing rod.

In witness whereof I have hereunto set my hand.

ARTHUR C. HOPKINS.
